UNITED STATES PATENT OFFICE.

VIOLETTE F. WRIGHT, OF PHILADELPHIA, PENNSYLVANIA.

DESIGN FOR A DOLL.

Application filed September 17, 1924. Serial No. 10,810. Term of patent 7 years.

To all whom it may concern:

Be it known that I, VIOLETTE F. WRIGHT, a citizen of the United States, residing at Philadelphia, in the county of Philadelphia and State of Pennsylvania, have invented a new, original, and ornamental Design for a Doll, of which the following is a specification, reference being had to the accompanying drawings, forming part thereof, in which:

Fig. 1, is a view in elevation of a doll showing my new design.

Fig. 2, is a view in rear elevation of a doll showing my new design.

Fig. 3, is an edge view of the doll shown in Figs. 1 and 2.

I claim:

The ornamental design for a doll substantially as shown.

VIOLETTE F. WRIGHT.
